CIRCUIT INTERRUPTER

James M. Wallace, Braddock, Herbert L. Rawlins, Swissvale, and James M. Cumming and Wayne S. Aspey, Turtle Creek, Pa., assignors to Westinghouse Electric Corporation, East Pittsburgh, Pa., a corporation of Pennsylvania

Application June 24, 1941, Serial No. 399,452

19 Claims. (Cl. 200—89)

1

This invention relates, generally, to electric circuit interrupters and, more particularly, to automatic reclosing circuit breakers.

The copending application of J. M. Wallace and H. L. Rawlins, Serial No. 374,686, filed January 16, 1941, now Patent No. 2,475,765, July 12, 1949, and assigned to the same assignee as this application, discloses and claims a circuit breaker of this type, and the instant invention is primarily concerned with certain modifications and improvements in the structures of this copending application, and which can be used with other structures. Circuit breakers of this type, in general, are provided with separable contacts in a closed arc chamber, with electro-responsive means for separating the contacts but having a lost motion connection therewith to permit overtravel of the contacts dependent on the pressures developed by the arc. In addition, means are provided for automatically maintaining the breaker contacts separated in response to a predetermined number of successive circuit interrupting operations, and requiring a manual operation to reset the breaker contacts.

One object of this invention is to provide novel operating mechanism for a breaker of the type described.

Another object of this invention is to provide in a circuit breaker of the type described using a liquid arc extinguishing medium, and means utilizing such medium for controlling the rate of movement of the breaker contacts; novel means controlling the supply of fresh liquid to the arcing zone to insure replenishing of the liquid in this zone between circuit interrupting operations.

Another object of this invention is to provide in an automatic reclosing circuit breaker, novel means for controlling closing movement of the breaker contacts.

Another object of this invention is to provide a circuit breaker construction wherein the rating of the breaker may be readily changed.

Another object of this invention is to provide in a circuit breaker of the type described, novel means responsive to a predetermined number of successive circuit interrupting operations for causing the breaker contacts to be maintained in an open circuit position.

A further object of this invention is to provide a circuit breaker of the type described which is compact and relatively simple in structure, yet safe and efficient in operation.

These and other objects of this invention will become more apparent upon consideration of

2

the following detailed description of a preferred embodiment thereof, when taken in connection with the attached drawing, in which:

Figure 1 is a substantially central vertical section through a circuit breaker embodying this invention with certain parts thereof shown in elevation;

Fig. 2 is a partial elevational view of the operating mechanism shown in Fig. 1;

Fig. 3 is a transverse sectional view of the breaker shown in Fig. 1 taken substantially on the line III—III thereof with certain parts omitted.

Fig. 4 is a fragmentary sectional view of the lockout integrating mechanism employed in the breaker shown in Fig. 1;

Fig. 5 is a view like Fig. 4 but showing the parts of the mechanism in a different position from that shown in Fig. 4; and

Fig. 6 is also a partial sectional view illustrating the mechanism of Figs. 4 and 5 in a still different position of the parts thereof.

The circuit breaker constituting this invention is shown by way of example as being mounted in a tubular insulating casing 2 which may be of any desired insulating material, preferably porcelain or the like. The casing 2 is provided with a closed bottom and an open top, with the top being closed by a cover assembly 4, and the bottom of the casing having associated therewith a terminal assembly 6. Intermediate the ends of the casing 2 there is provided a cylindrical surface 8, and a supporting bracket 12 is adapted to be clamped around this cylindrical surface with resilient material 10 interposed between the clamp 12 and the outer casing wall to prevent damage thereto.

The terminal assembly 6 at the bottom of the casing includes a terminal bolt 14 of conducting material adapted to extend through a substantially central aperture in the bottom casing wall, and the bolt is provided with an enlarged head 18 interiorly of the casing, with packing material 20 interposed between the head 18 and the bottom wall of the casing. A nut 22 and washer 24 cooperate with bolt 14 to retain the same in position, and a conductor 28 may be secured to the bolt, for example, as by a second nut 26. Bolt 14 is preferably provided with a substantially central bore 30 for the purpose of draining casing 2, the lower end thereof being adapted to be closed by a screw-threaded closure plug 32.

The upper end of casing 2 is ribbed, and a supporting flanged ring 34 is adapted to be secured to this ribbed portion of the casing, for

example, as by cast metal, or the like, 36. Supporting ring 34 is adapted to have cover assembly 4 secured thereto in any desired manner, not shown.

The casing and terminal structure 6 described above are substantially identical with those more particularly described and claimed in the above-mentioned copending application of H. L. Rawlins and J. M. Wallace, and in their copending application, Serial No. 346,300, filed July 19, 1940, now Patent No. 2,318,421, issued May 4, 1943, to the same assignee as this application.

Cover assembly 4 comprises an integral casting having a flange 38 formed integrally with the lower end thereof and adapted to seat on the upper end wall of casing 2 and extend over the interior of the casing. Flange 38 is also provided with integral outwardly extending ears (not shown) adapted to be bolted to ears formed on supporting ring 34. The cover assembly casting is provided with a hollow portion including the top wall 40, side walls 42, 43, and end walls 44 and 45, with the bottom of the hollow portion being open and located over the open top of casing 2. At one upper corner of the hollow portion of cover assembly 4, an inclined wall is provided with a threaded aperture for cooperation with a threaded filler plug 46, by means of which casing 2 may be filled with an arc extinguishing fluid. Top wall 40 of the hollow portion of the cover assembly is extended beyond the hollow portion and slightly inclined downwardly as at 48 to form the top wall of a sleet hood portion having side walls 52 and 53. The top wall 48 of the hood portion terminates in an angularly downwardly extending lip 59, for a purpose to be hereinafter described.

As appears from Figs. 1 and 3 of the drawing, flange 38 of the cover assembly 4 has portions which extend over the open top of casing 2, and these portions are adapted to insulatingly support the circuit breaker contacts and operating mechanism, for example, as by the tubular insulating spacer sleeves 54. The spacer sleeves 54 have the opposite ends thereof threaded for cooperation with screws 56 and 58, to secure the spacers to flange 38 and the upper leg 105 of a U-shaped supporting frame 60, respectively. The other leg 103 of U-shaped frame 60 is secured to one end of a generally rectangular frame 64, and the other end of this frame is preferably formed integral with the top cap 66 of an interrupter chamber 68.

The interrupter chamber 68 includes an insulating tube 70 of fiber or the like, having one end threaded into top cap 66, and having the other end threadedly received in a bottom terminal cap 74. Top cap 66 is provided with a substantially central aperture 69 for closely slidably receiving a contact piston rod 72, and the cap is also provided with spaced outlet apertures 73 adapted to be controlled by a sliding valve plate 102, normally biased by coil compression spring 104 into engagement with the adjacent end of insulating tube 70. The lower end cap 74 of the interrupter chamber is provided with inlet passages 76, and with a substantially centrally located threaded aperture for receiving the threaded end of an adjustable fixed contact 78 which is secured in position, for example, as by a lock nut 80. The outer end of end cap 74 is reduced in size to form a shoulder 82 on which is seated one end of a coil compression spring 84 with the other end of this spring bearing against the head 18 of terminal bolt 14.

Spring 84 should be of some good resilient conducting material, such, for example, as a copper alloy or the like.

The lower end of contact piston rod 72 is provided with a socket for receiving the upper end of contact rod 86, secured in the socket, for example, as by a rivet 88. The lower end of contact rod 86 is enlarged to form a contact head 90. A liquid directing piston 92 is provided with a central aperture 91 so that the piston may be slidably mounted on contact rod 86 for movement between contact head 90 and the lower end of contact piston rod 72. The lower end of contact piston rod 72 is counterbored to receive a coil compression spring 93 which normally operates to bias liquid directing piston 92 towards contact head 90. As shown, piston 92 is provided centrally with a hollow portion to which access is obtained by means of a plurality of top apertures 94, and a single lower aperture 95 concentric with contact head 90 so as to form an annular liquid passage therewith. Liquid director piston 92 may have a peripheral slot for the reception of a piston ring 96 to prevent leakage of liquid between the piston and inner wall of tube 70. A stop ring 98 is secured in position between the lower end of insulating tube 70 and lower end cap 74 and, as shown, projects inwardly so as to form a stop for liquid director piston 92, so that when the contacts are closed, the piston is maintained in a position intermediate the limits of its movement on contact rod 86. The inlet apertures 76 in cap 74 are adapted to be controlled by a check valve plate 100 freely mounted between the end wall of end cap 74 and stop ring 98. The interrupter chamber 68 described above is substantially identical with that described and claimed in the above-mentioned copending application of J. M. Wallace and H. L. Rawlins, Serial No. 374,636, now Patent No. 2,475,765 except that in the interrupter chamber herein described, valve plate 102 is spring biased in one direction, rather than being frictionally associated with contact piston rod 72 as in the said copending application.

The operation of the interrupter chamber herein disclosed and illustrated, is substantially the same as that in the above-identified copending application and comprises briefly utilization of fluid pressures generated by an arc drawn, to obtain contact separation. This is accomplished by the instant structure because it will be observed that as soon as contact piston rod 72 is moved upwardly and contact head 90 moves out of engagement with fixed contact 78 to strike an arc, the action of such an arc on the arc extinguishing liquid within the chamber, such, for example, as oil or the like, will decompose the same to generate a gas which will build up a pressure within chamber 68. As soon as this pressure builds up, it will obviously force check valve plate 100 and valve plate 102 outwardly relative to insulating tube 70 to close both the inlet and outlet apertures 76 and 73, respectively. Outward movement of valve plate 102 readily occurs because the upper side of this plate is vented by aperture 103. Accordingly, such pressures within the chamber will act on contact piston rod 72 in a piston-like manner to force the same to move outwardly of the chamber, and thereby increase the contact separation. In the upward movement of contact rod 86, liquid director piston 92 remains stationary until contact head 90 engages the upper wall of the director to thereby draw the arc out to an optimum length

before moving the director to cause a flow of liquid through apertures 94 and 95 into the arc to extinguish the same. Contact piston rod 72 and contact rod 86 will be moved outwardly by the pressure developed within arc chamber 68 until the combined action of attenuation of the arc and flow of liquid therethrough cause extinction. As soon as the arc is extinguished, the contact piston rod 72 is adapted to be moved downwardly towards fixed contact 78 in a manner to be hereinafter further described, and since pressure is no longer being generated within the chamber, spring 104 will be free to move valve plate 102 downwardly to open outlet passages 73 and permit exhaust of gases and used liquid out of the upper end of the arc chamber. This up-flow of gas and used liquid from the chamber will be taken care of by an in-flow of fresh liquid through inlet apertures 76 which will cause check valve plate 100 to be unseated due to the pressure at the bottom of the casing because of the head of liquid therein, and especially because of the difference in pressure due to the difference in the head of liquid between inlet apertures 76 and outlet apertures 73. Consequently, it can be seen that the fluid pressure developed by the arc is utilized in this interrupter to obtain contact separation, and that during a closing operation of the breaker contacts, the used arc extinguishing fluid within the chamber is replaced by fresh fluid from casing 2.

As previously stated, the substantially U-shaped supporting frame member 60 is secured to the upper end of rectangular supporting frame 64, and the frame member 60 is for the purpose of supporting a solenoid coil 112. The upper and lower legs 106 and 108 of supporting member 60 are connected by spaced integral legs 10 positioned at one side thereof, so that the solenoid coil 112 may be assembled with support 60 by merely slipping the entire coil between legs 108 and 106 through the open side of support 60. The legs 106 and 108 of the U-shaped frame 60 are provided with aligned apertures adapted to coincide with the central bore provided in solenoid coil 112, and a securing sleeve 114, of insulating material, is adapted to be inserted through the aperture in leg 108 of the U-shaped support 60 into engagement with a shouldered plug 116 seated against a shoulder provided about the aperture through leg 106 of U-shaped supporting frame 60. Securing sleeve 114 is maintained against movement downwardly from the supporting frame 60, as viewed in Fig. 1, by the connection of rectangular frame 64 thereto, inasmuch as the end plate 118 of this frame is provided with a shouldered aperture, with the adjacent end of securing sleeve 114 seated on the shoulder of this aperture to prevent movement thereof with respect to U-shaped frame 60. Frame 60 is of magnetic material to form a stationary frame for coil 112 as well as a support therefor. Rectangular frame 64 is secured to the lower leg 108 of U-shaped frame 60, for example, as by screws 62, or the like. It will be noted that solenoid coil 112 is provided with a plurality of taps 119 which are connected to different sections of the coil and located away from the connecting legs 110 of the U-shaped support 60, at the open side thereof so as to be readily accessible for the purpose of changing the coil connections when desired. Rectangular supporting frame 64 is provided with the side plates 120 integral with top plate 118 at one end there-

of, and with top cap 66 for the interrupter chamber at the other end thereof.

The upper end of contact piston rod 72 is peripherally grooved as at 122 to form a notch and a latch projection 124 at the upper end thereof, for cooperation with a latch lever 126. The latch lever is adapted to be pivotally mounted on top end cap 66 of the interrupter chamber, for example, as by a pivot pin 128, and a coil spring 130 is wound about pivot pin 128 with the ends thereof engaging end cap 66 and latch lever 126, respectively, for biasing the latch lever in a clockwise direction about its pivot, as viewed in Fig. 1. The latch lever is provided with a plurality of latch lugs 132 and 134 for cooperation with the latch projection 124 on the upper end of contact piston rod 72, and with the core of solenoid coil 112. A contact operating rod 136 is rigidly secured to contact piston rod 72 and 10 extends from the upper end thereof through a sleeve 137 extending through the central opening of solenoid coil 112 and securing sleeve 114. The lower end of sleeve 137 is enlarged as shown at 138 to receive the upper end of a coil compression spring 144, with the lower end thereof bearing against the bottom wall of a tubular solenoid core member 140. The tubular solenoid core 140, which is of magnetic material, has the bottom wall thereof apertured to be slidably 20 mounted on contact operating rod 136, and has adjacent the upper end thereof a peripheral inwardly extending rib 142 of a size to closely engage the outer surface of enlarged portion 138 of sleeve 137. Adjacent the lower end of solenoid core 140 are radially directed vent apertures 146, for a purpose to be hereinafter described. 25

In the operation of the mechanism thus far described, it will be apparent that upon the occurrence of predetermined circuit conditions, 40 solenoid coil 112 will become sufficiently energized to attract core 140 and cause it to move upwardly on operating rod 136 and compress spring 144 between the core and sleeve 137. Furthermore, because of the close fit between core 140, securing sleeve 114 and enlarged portion 138 of sleeve 137, and since these parts are all immersed in the arc extinguishing fluid, it will be obvious that upward movement of core 140 will be relatively slow because of the necessity 45 of displacing the fluid within securing sleeve 114 through the relatively small clearance between the core and sleeve. However, after sufficient movement of the core upwardly so that rib 142 clears the upper end of enlarged sleeve portion 138, there will then be a relatively large annular 50 passage through core 140 and outlet apertures 146 for liquid entrapped in securing sleeve 114, so that further movement of core 140 upwardly will take place at a relatively rapid rate. During 55 this rapid movement of the core, the bottom wall thereof will engage the lower end of enlarged sleeve portion 138 to cause movement of the sleeve upwardly with the core, and engagement of the upper end of the sleeve with shoulder 147 formed on contact operating rod 136, will thus 60 quickly separate contact head 90 from fixed contact 78. This movement of contact head 90 by solenoid core 140 away from fixed contact 78 need be but a small amount, because as soon as 65 the contacts are separated sufficiently to draw an arc, the pressure generated by such an arc operates to increase the contact separation sufficiently to extinguish the arc. Obviously because 70 of the sliding connection of solenoid core 140 with respect to contact operating rod 136, the

contact operating rod and contact head 98 are permitted to have a considerable over-travel independent of solenoid core 140 in response to pressures built up within the interrupter chamber 68. As soon as the arc is extinguished and the pressure drops within interrupter chamber 68, contact operating rod 136 is permitted to move downwardly to reclose the contacts. However, its downward motion is halted by engagement of latch projection 124 at the top of contact piston rod 72 with upper latch lug 132. In the meantime, solenoid core 140 returns very slowly under the biasing forces of gravity and spring 144, to the position shown in Fig. 1 because of the dashpot action thereof in securing sleeve 114, so that considerable time must elapse until the solenoid core 140 moves down into engagement with the upper end of latch lever 126, and thereby cause counterclockwise rotation of the latch lever to disengage its upper lug 132 from contact piston rod projection 124. This permits the projection 124 to drop down slightly with contact operating rod 136, and into engagement with the lower lug 134 on latch lever 126, where it is held until further downward movement of solenoid core 140 causes further counterclockwise movement of the latch lever until projection 124 is released from lug 134, whereupon the contact head 98 is permitted to move into engagement with fixed contact 78. Incidentally, it will be noted that upper lug 132 of latch lever 126 serves as the support for preventing undue downward movement of solenoid core 140.

The reason why a plurality of lugs 132, 134 are provided on the latch lever to successively halt downward movement of contact head 98 towards fixed contact 78, is that it is necessary to maintain the contacts separated during the time delay period before reclosure, a sufficient distance apart so that the dielectric therebetween will be capable of safely withstanding circuit voltage. Because of contamination and deterioration of the dielectric on the interruption of high current arcs, this distance is quite large. On the other hand, it is desired to make the time delay between a circuit interrupting operation and a reclosure of the circuit as long as possible with the available time delay means including the dashpot comprising solenoid core 140 and securing sleeve 114. Lug 132 on the latch lever, therefore, is positioned to engage the moving contact to hold it separated from fixed contact 78 a distance corresponding to the safe gap therebetween according to the dielectric being used. If lug 134 were not also provided on the latch lever, then the time delay between a circuit interrupting operation and a reclosure of the breaker contacts would be too short, and accordingly, to lengthen this period, the second lug 134 is provided for momentarily delaying reclosure of the breaker contacts after release of the moving contact from lug 132, to thereby obtain a longer time delay in reclosing without undue danger of flashover, inasmuch as the period of time which lug 134 operates to maintain the breaker contacts separated is so short that ionization of the path between the breaker contacts does not have time to be completed prior to reclosure of the contacts. Also on interruption of low currents, the pressure may be insufficient to move contact projection 124 as high as latch lug 132 and since the dielectric will not be unduly impaired by low current interruptions, engagement with latch lug 134 will provide a safe gap between the contacts while using full time delay on reclosure. This feature of the inven-

tion together with the special construction of arc chamber 68 are disclosed and claimed in application Serial No. 562,798, filed November 10, 1944, now Patent No. 2,442,477, June 1, 1948, which is a division of this application.

The upper end of contact operating rod 136 is pivotally secured as by pivot pin 150 to one end of a pair of insulating links 148, with the other ends of the links being connected to an angled 10 crank lever 152, for example, as by the pivot pin 153. Crank lever 152 is pivotally mounted at its other end on a shaft 154 extending across the hollow portion of the top cover casting, and its outer ends are mounted in apertures provided in 15 the side walls 42 and 43 of the cover hollow portion, with the outer ends of these apertures being closed by screw plugs 156 to prevent relative endwise movement of shaft 154. Angled crank lever 152 is rotatably mounted on shaft 154, and a 20 generally U-shaped yoke 158 has the leg portions thereof also rotatably mounted on shaft 154, with one leg of yoke 158 pivotally connected to one end of toggle links 160 by a pivot pin 162, and the other ends of these toggle links being pivotally connected at 164 to a toggle lever 166, which is, in turn, secured on the squared end of a shaft 168 rotatably mounted in an angled portion of end wall 45 of the cover assembly in a bearing sleeve 172, by a bolt 170, which also acts 25 to secure an operating handle 174 to the other squared end of shaft 168. Operating handle 174 is provided at the outer end thereof with a hook eye aperture 176 for the reception of a hook stick or other operating member. Actuating handle 174 is limited in its movement in a counterclockwise direction by a stop screw 178 which may be secured in an adjusted position, for example, as by a lock nut 180.

A pair of concentric coil springs 182 and 184 are provided about shaft 154 within the hollow portion of the cover assembly 4, with one end 186 of the outer large diameter coil spring 184 engaging flange 38 of the cover assembly, and the other end 188 thereof engaging the connecting portion 45 189 of yoke 158, to thereby bias the yoke for movement about shaft 154 in a counterclockwise direction. This movement of the yoke is normally prevented by virtue of the toggle formed by links 160 and 166 being below their dead-center position when actuating handle 174 is in engagement with stop screw 178. One end 190 of the smaller diameter inner coil spring 182 is extended to engage the angled portion of crank lever 152, and the other end of this spring also 50 engages the connecting portion 189 of yoke 158, so that when the yoke is locked by toggle levers 160 and 166 against movement in a counterclockwise direction, biasing spring 182 will operate to bias crank lever 152 downwardly or in a clockwise direction relative to shaft 154, to thereby bias contact actuating rod 136 and contact head 98 downwardly, and cause engagement of the contact head with fixed contact 78.

The circuit through the interrupter herein disclosed extends from a terminal bracket 194 secured to the top cover assembly, for example, as by a screw 198 with the bracket having a terminal socket 196 for the reception of a line conductor, through the cover casting, by way of a conductor 200 to one tap 119 of solenoid coil 112, through the coil, conductor 202 to contact piston rod 72, contact rod 86, contact head 98, fixed contact 78, end cap 74, compression spring 84, terminal bolt 14, to another line conductor 28.

Thus, it can be seen that the solenoid coil 112 is connected in series in the circuit including the breaker contacts, and as shown, the whole coil is connected in series, inasmuch as the end taps of the coil are used, and, therefore, the connection is for the lowest rating of the breaker which can be obtained with the coil employed, inasmuch as the maximum flux generating capacity of the coil is employed to thereby obtain sufficient force to separate the contacts on relatively low currents. To obtain higher current ratings, it would be merely necessary to connect conductor 202 or 200 to other taps 119 of the coil to utilize smaller portions of the coil winding. It will be noted that the entire circuit breaker mechanism including the breaker contacts and interrupting chamber are supported as a unit with the casing cover assembly 4, so that they may be removed with the cover from the casing when desired by merely unfastening the securing means of the cover to support 34 on the casing. Another feature of the particular supporting means for the circuit breaker mechanism illustrated, is the specific support of the solenoid coil permitting ready replacement thereof by another similar coil, or by a coil having a different number of turns to thereby change the available ratings of the breaker. In order to remove coil 112, it is merely necessary to remove screws 62 holding U-shaped frame 60 and rectangular frame 64 together. This permits securing sleeve 114 to drop downwardly out of U-shaped frame 60, and then by removing one pivot pin, for example, the pivot pin 150, the entire contact operating rod and sleeve 137 can be slipped out of U-shaped frame 60 through apertures in legs 106 and 108 of the frame, whereupon coil 112 may be slipped laterally out of the open side of U-shaped frame 60. To insert a new coil, it is simply necessary to slide it in the open side of U-shaped frame 60 until the bore therethrough is aligned with the apertures in legs 106 and 108 of the frame, whereupon contact actuating rod 136 and securing sleeve 114 may be inserted through the apertures and through the bore in the coil, and rectangular frame 64 secured to the lower leg 108 of the U-shaped supporting frame to thereby firmly secure the solenoid coil in operative position. Consequently, in order to remove the coil, it is only necessary to remove two screws 62, and one pivot pin 150. This feature of the invention is disclosed and claimed in application Serial No. 561,384, filed November 1, 1944, now Patent No. 2,468,852, May 3, 1949, which is a division of this application.

The operation of contact biasing spring 182 mounted on shaft 154 in cover assembly 4 is believed to be obvious from the foregoing. In other words, when the circuit is interrupted by energization of solenoid coil 112 sufficiently to raise core 140 and separate the contacts against the bias of spring 182, this spring will be effective as soon as the circuit is interrupted to move the contact operating rod and contact head 90 downwardly towards fixed contact 78, until projection 124 on contact piston rod 12 is engaged by latch lug 132, whereupon reclosure of the contacts will be delayed until the latch is released by solenoid core 140 in the manner previously described.

In the event an overload occurs on the circuit which is not self-clearing but continues after a predetermined number of successive interrupting operations, there is provided means for tripping the toggle which normally prevents rotation of

yoke 158, so that spring 184 becomes effective to rotate the yoke in a counterclockwise direction to the dotted line position shown in Fig. 1 and, consequently, raise crank lever 152, by engagement of the cross bar 189 of the yoke with a projection 191 on the lever, together with contact actuating rod 136 and contact head 90 to a position wherein the contact head is maintained out of engagement with fixed contact 78, because coil spring 182 will be ineffective to reclose the contacts. The means for tripping the toggle includes a cylindrical tube 204 threadedly mounted in the upper leg 106 of U-shaped support 60, and provided with an inlet aperture 208 in the bottom wall thereof controlled by a ball-check valve 210 to permit flow of liquid into tube 204, but preventing out-flow of liquid. A piston member 206 is slidably mounted within cylindrical tube 204, and the upper end thereof is provided with a plurality of spaced peripheral grooves 214, 216, and 218, respectively, to form a ratchet-like portion on the piston accessible through a side opening 212 in cylindrical sleeve 204. A pawl guide rod 220 is also secured to leg 106 of U-shaped support 60 between cylindrical sleeve 204 and contact operating rod 136, for guiding a substantially U-shaped pawl member 222, having the connecting portion thereof slotted, as shown at 224 to receive the contact operating rod and with the ends of the slot extending into the legs of the U-shaped pawl but reduced in width, as shown at 226, to more closely fit guide rod 220. Contact actuating rod 136 is adapted to extend through the slot 224 so that the bottom portion of the pawl seats on flange 232 formed on the upper end of sleeve 137 slidable on the contact actuating rod. Guide rod 220 is formed with an intermediate shoulder on which a washer 228 is adapted to be seated, with a coil compression spring 230 engaging between washer 228 and the lower leg of U-shaped pawl 222 to normally maintain the pawl in the position shown in Fig. 4. In the operation of the circuit breaker, it will be observed that each time solenoid core 140 is drawn upwardly to open the circuit and engage the lower end of enlarged portion 138 of sleeve 137 to move the same upwardly, that it will cause a tilting of pawl 222 against the bias of spring 230, so that the upper end thereof moves towards piston 206 and engages one of the grooves in the pawl portion thereof, so that continued upward movement will move the entire piston upwardly and thereby unseat ball-check valve 210 and cause a predetermined amount of liquid to be drawn in the lower end of sleeve 204. As soon as the circuit is interrupted, and the contact actuating rod and associated parts are moved downwardly by biasing spring 182 in the manner previously described, compression spring 230 on guide rod 220 is operative to withdraw the upper leg of pawl 222 from the notch 214 in piston 206, so that the piston remains at the position to which it has been moved, while the contacts are reclosed. Now if the fault on the circuit has been removed, piston 206 will gradually sink to the position shown in Fig. 4 by displacement of the liquid below the piston through the relatively small clearance between the piston and cylindrical sleeve 204, so that eventually it will attain its original position shown in Figs. 1 and 4. However, in the event the fault in the circuit has not cleared upon the first reclosure of the breaker contacts, they will again be opened by solenoid 112, and this time pawl 222 will engage

notch 216 in piston 206, as shown in Fig. 5, inasmuch as the piston will not have had time to sink to its original position and the piston will be moved upwardly to the position shown in Fig. 6 of the drawing. As soon as the arc is extinguished, the contacts will again be reclosed by biasing spring 182, and if the fault has cleared, piston 206 will again slowly sink to its original position as before. However, if the fault has not cleared, before piston 206 has an opportunity to sink much below the position shown in Fig. 6, the contacts will again be opened, and this time pawl 222 will be pivoted into engagement with the lower notch 218 in piston 206 and cause the same to be moved upwardly a further amount and into engagement with the knee of the toggle formed by levers 160 and 166 to move the knee of the toggle overcenter, thereby releasing spring 184 and permitting the same to rotate yoke 158 and move the toggle levers and contact operating rod to the dotted-line position shown in Fig. 1 of the drawing wherein the breaker contacts are maintained by spring 184 in an open circuit position.

It will be observed that ordinarily actuating lever 174 is maintained entirely within the hood formed integral with top cover assembly 4, but upon tripping of the toggle constituted by levers 160 and 166, the actuating lever 174 will be moved in a clockwise direction about its pivot axis 170 to project below the hood, and thereby give a readily visible indication of the fact that the breaker contacts are now maintained in an open circuit position. When piston 206 has tripped the toggle, it will be observed that since contact operating rod 136 is maintained in an upper position, pawl 222 will be maintained in engagement with notch 218 on piston 206 to maintain the piston in its uppermost position. Accordingly, when it is desired to manually reclose the breaker contacts by movement of operating lever 174 in a counterclockwise direction to reset the toggle levers to the position shown in full lines in Fig. 1, it will be observed in the first place, that in the event it is thus attempted to close the circuit while an overload is present, that the breaker is trip-free in that it is free to open against the bias of contact biasing spring 182 irrespective of the position of actuating lever 174. In the second place, it will be noted that since piston 206 has had but a little time to move downwardly from its outermost position with respect to cylindrical sleeve 204, that in the event the breaker is reclosed manually upon an overload in the circuit, that on the consequent circuit interruption and movement of the contact operating rod and associated parts upwardly, pawl 222 will be caused to engage the lower notch 218 of piston 206 to thereby move the toggle overcenter and again permit spring 184 to maintain the contacts in an open position.

Thus, it can be seen that the circuit breaker herein disclosed is capable of automatically opening the circuit with an inverse time delay due to the dashpot action of core 140 in securing sleeve 114, and yet the contacts are separated with a relatively fast action due to the venting of the dashpot formed by core 140 and sleeve 114 adjacent the end of its stroke. This feature is the invention of J. M. Wallace and is more particularly disclosed and claimed in his co-pending application, Serial No. 399,453, filed June 24, 1941, now Patent No. 2,333,604, issued November 2, 1943, to the same assignee of this invention. Following a circuit interrupting op-

eration, the breaker contacts are automatically reclosed with a time delay also due to the dashpot action of core 140 and sleeve 114, while maintaining substantially to adjacent the end of the timed period a safe gap between the breaker contacts. Also, in response to a predetermined number of closely successive circuit interrupting operations, novel means are provided for maintaining the breaker contacts in an open position, which includes a biasing means normally held inactive by a toggle which is moved overcenter by a piston actuated a predetermined amount upon each interrupting operation. The arc chamber herein disclosed is provided with an outlet valve which is positive in operation, and the electro-responsive solenoid contact opening means is supported in a manner to render the same readily replaceable, and is provided with a plurality of taps so that the rating of the breaker may be readily changed. The specific arrangement of the contact closing spring and the spring for maintaining the contacts separated is especially important with respect to space considerations and efficiency of operation.

An operation counter 234 is adapted to be mounted on the end wall 45 of the hollow portion of cover assembly 4 and to be located beneath the hood portion thereof so as to be readily visible from the exterior of the breaker while protected from the elements by the hood. This operation counter may be of any well known type provided with an actuating crank lever 236, mounted on an operating shaft extending through the angled portion of wall 45 like shaft 168, and with crank 236 pivotally connected to an operating link 238, which, in turn, is connected to pawl 222, so as to actuate the counter on each circuit interrupting operation of the breaker. The connecting link 238 is provided with an insulating portion 240 to insulate the counter from pawl 222.

There is preferably provided within the hollow portion of cover assembly 4 in a socket 242 provided therefor on top wall 40, a lightning arrester assembly, which may be of any well known type including electrodes 256 spaced by an insulating plate 258 to form a gap in series with a porous block 260, in the circuit between top wall 40 of the cover and terminal 244 of the assembly. A tubular insulating sleeve 262 is positioned between the assembly and the side wall of socket 242, and insulating disk 270 supports terminal 244, and is secured to the cover assembly 4 by screws 266, with a sealing gasket 264 therebetween to maintain the arrester assembly in socket 242. A shunt 268 connects terminal 244 and a contact plate 271, and this plate is maintained in contact with block 260 by a spring 272. The arrester terminal 244 is connected by conductor 248 to the top leg 106 of U-shaped frame 69 to thereby form a circuit bypassing solenoid coil 112. This obviously will prevent the solenoid coil from opening the breaker contacts in response to surges inasmuch as the coil will cooperate with the shunt circuit through the arrester assembly to bypass such surge currents around the coil and limit the voltage across the coil insulation, and such surges will be ineffective to cause a circuit interrupting operation of the breaker. The arrester assembly herein disclosed utilizes a single series porous block and gap of the type shown in the plural series block and gap arrester shown in the patent to L. R. Ludwig, et al., No. 2,135,085, issued November 1, 1938. It will be understood that plural series porous block and gap assemblies may be used with this

circuit breaker, if desired. This feature of the invention is disclosed and claimed in our divisional application, Serial No. 737,874, filed March 28, 1947, now Patent No. 2,575,739, November 20, 1951, and assigned to the same assignee of this invention.

Also positioned beneath the hood portion of the cover assembly is a tubular sight gauge glass 250, held in position against an integral lug 248 on end wall 45 of the cover assembly, by an apertured threaded plug 249, and an indicating rod 252 is slidably mounted through the apertured plug and tubular sight glass, and is provided with a float 254 secured to the lower end thereof within casing 2 so that the level of liquid within casing 2 may be readily determined from the exterior thereof by inspection of the sight glass beneath the hood portion of the cover assembly.

Thus, there is provided in a single unit an automatic reclosing circuit breaker characterized by its ability to automatically maintain the breaker contacts in an open circuit position in response to faults which continue a predetermined period of time, and by its inverse time current tripping characteristics with predetermined time delay in reclosing of the circuit, together with means incorporated in the unit to protect the coil insulation and prevent operation of the breaker in response to the occurrence of surges in the circuit. Moreover, the cover assembly for the breaker casing 2 is arranged with a sleet hood portion at one side thereof to conceal an operating handle which is projected into view upon lock-open operation of the breaker contacts to indicate this condition, and also houses liquid level indicating means, as well as means for indicating the number of breaker operations.

Having described a preferred embodiment of this invention in accordance with the Patent Statutes, it is desired that it be not limited to the particular embodiment herein disclosed, inasmuch as it will be obvious, particularly to persons skilled in the art, that many changes and modifications may be made in this particular embodiment without departing from the broad spirit and scope of the invention. Therefore, it is desired that the invention be interpreted as broadly as possible and that it be limited only by the prior art and by what is expressly set forth in the following claims.

We claim as our invention:

1. In an automatic reclosing circuit breaker, separable contacts, electro-responsive means for separating said contacts, means responsive to a circuit interrupting operation for automatically reclosing said contacts, normally inactive means adapted when activated to prevent closure of said contacts, control means for rendering said last-mentioned means active including fluid piston and cylinder members, means directly mechanically engageable with one of said members only during separation of said contacts to move said one member in one direction relative to the other the same predetermined amount on each circuit interrupting operation, said one member being biased to slowly move in the opposite direction to its normal position, and said one member upon movement in said one direction an amount determined by a predetermined number of successive interrupting operations adapted to engage said normally inactive means to render the same active to prevent reclosure of said contacts.

2. In an automatic reclosing circuit breaker, a relatively stationary contact, a contact rod slidably movable for causing engagement and dis-

engagement of a movable contact supported thereon with respect to said stationary contact, electro-responsive means for moving said rod in a direction to separate said contacts, means responsive to a circuit interrupting operation for moving said rod in an opposite direction to automatically reclose said contacts, normally inactive means for preventing closure of said contacts, control means for rendering said last-mentioned means active including fluid piston and cylinder members, means responsive to a circuit interrupting operation for moving one of said members in one direction relative to the other a predetermined amount, said last-mentioned means including a ratchet formed on said one member, a pawl guide extending generally in the direction of movement of said one member, a pawl slidably and tiltably mounted on said guide, means biasing said pawl out of engagement with said ratchet, a shoulder on said contact rod engageable with said pawl upon movement thereof in a direction to separate said contacts for tilting said pawl into engagement with said ratchet and moving said pawl along said guide and said one member in one direction relative to the other member a predetermined amount, said one member being biased to slowly move in the opposite direction to its normal position, and said one member upon movement in said one direction an amount determined by a predetermined number of successive interrupting operations adapted to engage said normally inactive means to render the same active to prevent reclosure of said contacts.

3. In an automatic reclosing circuit breaker, separable contacts, electro-responsive means for separating said contacts, means responsive to a circuit interrupting operation for automatically reclosing said contacts, resilient means for maintaining said contacts separated, overcenter toggle means for releasably maintaining said resilient means in an inactive condition, and means responsive to a predetermined number of circuit interrupting operations to cause movement of said toggle means overcenter to release said resilient means whereby to maintain said contacts separated.

4. In an automatic reclosing circuit breaker, separable contacts, electro-responsive means for separating said contacts, means responsive to a circuit interrupting operation for automatically reclosing said contacts, resilient means for maintaining said contacts separated, overcenter toggle means for releasably maintaining said resilient means in an inactive condition, means responsive to a predetermined number of circuit interrupting operations to cause movement of said toggle means overcenter to release said resilient means whereby to maintain said contacts separated, and one lever of said toggle means including an operating handle extension for resetting said toggle means.

5. In an automatic reclosing circuit breaker, separable contacts, electro-responsive means for separating said contacts, means responsive to a circuit interrupting operation for causing engagement of said contacts, resilient means for maintaining said contacts separated, overcenter toggle means for releasably maintaining said resilient means in an inactive condition, means responsive to a predetermined number of circuit interrupting operations to cause movement of said toggle means overcenter to release said resilient means whereby to maintain said contacts separated, said last-mentioned means including fluid piston and cylinder members, means en-

gagable with one of said members only upon separation of said contacts to move said one member in one direction relative to the other a predetermined amount, said one member being biased to slowly move in the opposite direction to its normal position, and said one member upon movement in said one direction an amount determined by a predetermined number of successive interrupting operations adapted to engage said toggle means to release said resilient means, manual means for resetting said toggle means to permit said contacts to move into engagement and release said one member, whereby said resilient means will be released in the event of the occurrence of a circuit interrupting operation upon manual resetting of said biasing means.

6. In a circuit breaker, separable contacts, electro-responsive means for separating said contacts, concentric coil springs one of which biases said contacts into engagement, means releasably maintaining said other coil spring inactive, said other spring when released being effective to maintain said contacts separated, and means responsive to a plurality of successive circuit interrupting operations for releasing said other coil spring.

7. In a circuit breaker, separable contacts, electro-responsive means for separating said contacts, a first resilient means reacting between a movably mounted support and at least one of said contacts, means releasably maintaining said support against movement whereby said first resilient means is effective to cause engagement of said contacts, a second resilient means biasing said movable support in a direction to cause said contacts to be separated, and means responsive to a plurality of successive circuit interrupting operations for releasing said movable support for movement by said second resilient means.

8. In an automatic reclosing circuit breaker, separable contacts, electro-responsive means for separating said contacts, means responsive to a circuit interrupting operation for automatically reclosing said contacts, normally inactive means for preventing closure of said contacts, control means for rendering said last-mentioned means active including fluid piston and cylinder members, an inlet for said cylinder member, a check valve for said inlet, means responsive to a circuit interrupting operation for directly mechanically engaging one of said members to move it in one direction outwardly relative to the other a predetermined amount to cause the same predetermined amount of fluid to be drawn into said cylinder member on each circuit interrupting operation, said one member being biased to slowly move in the opposite direction to its normal position, and said one member upon movement in said one direction an amount determined by a predetermined number of successive interrupting operations adapted to engage said normally inactive means to render the same active to prevent reclosure of said contacts.

9. In an automatic reclosing circuit breaker, separable contacts, electro-responsive means for separating said contacts, means responsive to a circuit interrupting operation for automatically reclosing said contacts, normally inactive means adapted when activated to prevent closure of said contacts, control means for rendering said last-mentioned means active including fluid piston and cylinder members, means responsive to a circuit interrupting operation for mechanically engaging one of said members to move said one member in one direction relative to the other the same

predetermined amount on each circuit interrupting operation, said one member being biased to slowly move in the opposite direction to its normal position, and said one member upon movement in said one direction an amount determined by a predetermined number of successive interrupting operations adapted to engage said normally inactive means to render the same active to prevent reclosure of said contacts.

10. In an automatic reclosing circuit breaker, separable contacts, electro-responsive means for separating said contacts, means responsive to a circuit interrupting operation for automatically reclosing said contacts, normally inactive means adapted when activated to prevent closure of said contacts, control means for rendering said last-mentioned means active including fluid piston and cylinder members, means including pawl and ratchet means cooperable with one of said members only during separation of said contacts to move said one member in one direction relative to the other the same predetermined amount on each circuit interrupting operation, said one member being biased to slowly move in the opposite direction to its normal position, and said one member upon movement in said one direction an amount determined by a predetermined number of successive interrupting operations adapted to engage said normally inactive means to render the same active to prevent reclosure of said contacts.

11. In an automatic reclosing circuit breaker, separable contacts, electro-responsive means for separating said contacts, means responsive to a circuit interrupting operation for automatically reclosing said contacts, normally inactive means adapted when activated to prevent closure of said contacts, control means for rendering said last-mentioned means active including fluid piston and cylinder members, means having lost motion with said contacts responsive to a circuit interrupting operation for mechanically engaging one of said members to move said one member in one direction relative to the other the same predetermined amount on each circuit interrupting operation, said one member being biased to slowly move in the opposite direction to its normal position, and said one member upon movement in said one direction an amount determined by a predetermined number of successive interrupting operations adapted to engage said normally inactive means to render the same active to prevent reclosure of said contacts.

12. In an automatic reclosing circuit breaker, a relatively stationary contact, a contact rod slidably movable for causing engagement and disengagement of a movable contact supported thereon with respect to said stationary contact, electro-responsive means for moving said rod in a direction to separate said contacts, means responsive to a circuit interrupting operation for moving said rod in an opposite direction to automatically reclose said contacts, normally inactive means for preventing closure of said contacts, control means for rendering said last-mentioned means active including fluid piston and cylinder members, means responsive to a circuit interrupting operation for moving one of said members in one direction relative to the other a predetermined amount, said last-mentioned means including a ratchet formed on said one member, a pawl guide extending generally in the direction of movement of said one member, a pawl slidably and tiltably mounted on said guide, means biasing said pawl out of engagement with

said ratchet, pawl actuating means having lost motion with respect to said contact rod for engaging said pawl upon movement of said contact rod in one direction to tilt said pawl into engagement with said ratchet and move said pawl along said guide and said one member in one direction relative to the other, means limiting movement of said one member by said pawl upon a single circuit interrupting operation to a predetermined amount, said one member being biased to slowly move in the opposite direction to its normal position, and said one member upon movement in said one direction an amount determined by a predetermined number of successive interrupting operations adapted to engage said normally inactive means to render the same active to prevent reclosure of said contacts.

13. In an automatic reclosing circuit breaker, separable contacts, electro-responsive means for separating said contacts, means responsive to a circuit interrupting operation for automatically reclosing said contacts, biasing means for maintaining said contacts separated, overcenter toggle means for releasably maintaining said biasing means in an inactive condition, means responsive to a predetermined number of circuit interrupting operations to cause movement of said toggle means overcenter to release said biasing means whereby to maintain said contacts separated, and manually operable means operatively associated with said toggle to reset the same.

14. In a circuit breaker of the type described, a supporting casing having an open end and a closed end, a cover for the open end of said casing having a hollow portion overlying and opening toward said casing, a circuit breaker mechanism in said casing and supported from said cover to form therewith a removable unit, said mechanism including separable contacts and electro-responsive contact opening means, and resilient means supported in the hollow portion of said cover for maintaining said contacts separated, overcenter toggle means for releasably maintaining said resilient means in an inactive condition, and means responsive to a predetermined number of circuit interrupting operations to cause movement of said toggle means overcenter to release said resilient means whereby to maintain said contacts separated.

15. In an automatic reclosing circuit breaker having separable contacts, means responsive to predetermined circuit conditions for causing separation of said contacts to open the circuit, means responsive to a circuit interrupting operation for automatically causing a circuit closing operation of said contacts, means rendered operative in response to a predetermined number of closely successive circuit interrupting operations for automatically preventing reclosure of said contacts, manual means for causing reclosure of said contacts after operation of said reclosure-preventing means, and means for positively rendering said reclosure-preventing means operative to prevent contact reclosure in response to a first circuit interrupting operation closely following a manual reclosure after an automatic reclosure-preventing operation.

16. In an automatic reclosing circuit breaker having separable contacts, means responsive to predetermined circuit conditions for causing separation of said contacts to open the circuit, means responsive to a circuit interrupting operation for automatically causing a circuit closing operation of said contacts, means rendered operative in

response to a predetermined number of closely successive circuit interrupting operations for automatically preventing reclosure of said contacts, manual means for causing reclosure of said contacts after operation of said reclosure-preventing means, and means for positively rendering said reclosure-preventing means operative to prevent contact reclosure in response to a first circuit interrupting operation for a predetermined time following a manual reclosure after an automatic reclosure-preventing operation, whereby at the end of said predetermined time said reclosure-preventing means will again be responsive only to said predetermined number of operations.

17. In an automatic reclosing circuit breaker having separable contacts, means responsive to predetermined circuit conditions for causing separation of said contacts to open the circuit, means responsive to a circuit interrupting operation for automatically causing a circuit closing operation of said contacts, integrating means adapted to be advanced a predetermined amount in response to each operation of said breaker, said integrating means being biased to slowly return to its normal position, lockout means responsive to advancement of said integrating means an amount greater than said predetermined amount by a predetermined number of closely successive operations of said breaker for automatically preventing reclosure of the breaker contacts, manual means for causing reclosure of said contacts following automatic operation of said lockout means, and means effective when said contacts are prevented from reclosing for preventing return movement of said integrating means and being responsive to closing movement of said contacts to permit return movement of said integrating means.

18. In an automatic reclosing circuit breaker, separable contacts, electro-responsive means for separating said contacts, means responsive to a circuit interrupting operation for automatically reclosing said contacts, resilient means for maintaining said contacts separated, overcenter toggle means for releasably maintaining said resilient means in an inactive condition, means responsive to a predetermined number of circuit interrupting operations to cause movement of said toggle means overcenter to release said resilient means whereby to maintain said contacts separated, one lever of said toggle means including an operating handle extension for resetting said toggle means, a casing for said circuit breaker having a hood portion positioned to normally receive said handle, and said handle being moved out of said hood portion by movement of said toggle overcenter to provide a clearly visible indication of the condition of said breaker when said contacts are maintained separated.

19. In an automatic reclosing circuit breaker, separable contacts, electro-responsive means for separating said contacts, means responsive to a circuit interrupting operation for automatically reclosing said contacts, biasing means for maintaining said contacts separated, overcenter toggle means for releasably maintaining said biasing means in an inactive condition, means responsive to a predetermined number of circuit interrupting operations to cause movement of said toggle means overcenter to release said biasing means whereby to maintain said contacts separated, manually operable means operatively associated with said toggle to reset the same, a casing for said circuit breaker having a hood

portion positioned to normally receive said manually operable means, and said manually operable means being moved out of said hood portion by movement of said toggle overcenter to provide a clearly visible indication of the condition of said breaker when said contacts are maintained separated.
